PLATE FINISHING MACHINE

Leonard G. Olander, Minneapolis, Minn., assignor to The Monometl Company, Incorporated, Minneapolis, Minn., a corporation of Minnesota

Application March 6, 1937, Serial No. 129,408

7 Claims. (Cl. 90—18)

This invention relates to a plate finishing machine and while the invention might have various applications, it particularly is designed for finishing or making a flat surface on a stereotype plate to bring said plate to the proper thickness and finish so that it can be properly placed in the printing form.

It is an object of this invention to provide a machine in which the printing plate is reciprocated beneath a rotating cutter and having supporting means for a plate-supporting member together with novel and accurate means for raising and lowering said last mentioned means.

It is another object of the invention to provide a machine having a frame, a cutter, an elongated member therein for positioning the plate to be finished relative to the cutter, said elongated member being supported by a plurality of swinging means pivoted thereto and to said frame.

It is a further object of the invention to provide a plate finishing machine comprising a rotating cutter, a plate-supporting member reciprocable past said cutter together with novel means for holding a plate on said plate carrying member adjacent said cutter.

It is still another object of the invention to provide a plate finishing machine comprising a rotating cutter, a plate-carrying member reciprocable past said cutter together with simple and efficient means for positioning said plate-carrying member and holding the same in desired position.

It is also an object of the invention to provide a plate finishing machine comprising a rotating cutter and means for receiving and discharging the shavings made by said cutter.

It is still another object of the invention to provide a plate finishing machine comprising a rotating cutter, a plate-carrying member reciprocable past said cutter together with means for stopping the movement of said parts if too great a cut is taken by said cutter.

These and other objects and advantages of the invention will be fully set forth in the following description made in connection with the accompanying drawings, in which like reference characters refer to similar parts throughout the several views and in which:

Fig. 1 is a view in side elevation of the machine;

Fig. 2 is a top plan view of the machine, some parts being broken away;

Fig. 3 is a top plan view of an elongated member used, some parts being broken away and others shown in horizontal section;

Fig. 4 is a vertical section taken on line 4—4 of Fig. 2 as indicated by the arrows;

Fig. 5 is a partial vertical section taken substantially on line 5—5 of Fig. 2 as indicated by the arrow;

Fig. 6 is a partial view mostly in side elevation as seen from the top of Fig. 2, some parts being broken away and others shown in vertical section;

Fig. 7 is a vertical section taken on line 7—7 of Fig. 2 as indicated by the arrows;

Fig. 8 is a vertical section taken on line 8—8 of Fig. 2 as indicated by the arrows; and

Fig. 9 is a vertical section taken on line 9—9 of Fig. 3 as indicated by the arrows.

Referring to the drawings, a machine is shown comprising a frame 20. While this frame might be variously made, in the embodiment of the invention illustrated it is shown as of elongated box form open at its top and is thus substantially rectangular in horizontal cross section and in transverse and longitudinal vertical section. The frame thus comprises vertical and parallel end walls 20a, parallel vertical side walls 20b and a substantially horizontal bottom 20c. Said side walls 20b have adjacent each end rectangular openings 20d therein, which openings are closed by removable plates or doors 21. The doors 21 at one side of said frame have offset clips 22 secured to one end, the offset portions of which extend along the inside of wall 20b. At their other ends said doors are provided with handles 23 inward of which is secured a spring catch or lock 24 having opposite resilient sides of V-shaped form with their open sides facing each other. Said catches or locks are adapted to be pressed between the spaced side portions 25a of keeper members 25 secured to the inner sides of walls 20b. After said V-shaped portions are pressed between portions 25a they expand so as to be held in members 25. The members 24 can be pulled outwardly by handle knob 23 so as to remove said doors 21. The doors 21 at the other side of frame 20 are shown as secured by removable headed screws 19 extending through said doors and threaded into the side wall 20b, said screws being shown as having slotted heads.

Said frame members 20b have journaled therein adjacent their upper ends rods 26 which extend between said walls. In the embodiment of the invention illustrated three of these rods are shown. Secured to these rods are swinging members or links 27, which members are pivoted at their upper ends on pivots 28 spaced similarly to rods 26 and carried in an elongated openwork

frame 29. The central member 27 is secured to a gear segment 27a having teeth at its periphery engaged by another gear 30 secured to a shaft 31 journaled in one of the side walls 20b and in a box 20e projecting therefrom, said shaft having secured at the outer side of said side wall a hand wheel 32. By turning hand wheel 32 gear or pinion 30 will be rotated, thus rotating segment 27a and swinging the attached link 27. This causes swinging movement of all of the links 27 and frame 29 is raised or lowered depending on the direction in which segment 27a is oscillated. Frame 29 normally moves downwardly by gravity. In order to hold said frame in the position to which it has been moved by hand wheel 32 it is engaged at one end by the end of a screw 33 threaded into one end wall 20a and having a knurled knob or wheel 34 secured to its end. A jamb nut 35 is threaded on screw 33, the same also having a knurled cylindrical handle, which jamb nut may be screwed against the side wall 20a. A nut 36 is shown on screw 33 at the inner side of end wall 20a. A hard plate 37 is secured to the end of frame 29 with which screw 33 engages. The frame 29 has side portions in one of which is formed a dove-tailed or angular guideway 29a. In the other side member a right angled guideway is formed and a member 38 having an inner angular face is secured to said side member by screws 39 extending through somewhat elongated holes in member 38. A gib strip 40 extends along the side of member 38 and is engaged by screws 41 extending through the outer vertical portion of the side of member 29. Screws 41 have slotted ends and may be adjusted to move member 38. The members 38 and guideway 29a form a guide for a slide 42 which forms a plate-carrying member. Member 42 has strips 43 rectangular in section secured along each side and at the top thereof by spaced screws 44. A right-angled member 45 is secured at the front end of member 42 by spaced screws 45b. Member 45 has a top flange overhanging the top surface of member 42, the front edge 45a of which is serrated as shown in Fig. 2. The member 42 has secured to its undersurface substantially midway thereof a nut 46. A screw 47 is threaded in nut 46 and has reduced end portions 47a journaled in the end portions of frame 29. Screw 47 projects at the rear end of frame 29 and has secured thereto a beveled gear 48 meshing with another beveled gear 49 secured to a shaft 50. Shaft 50 is journaled in portions of frame 29 and projects at one side thereof through a slot 20f formed in one of the side walls 55 20b. A pulley 51 is secured to the outer end of shaft 50 over which runs a belt 52 also running over a pulley 53 secured to a shaft 54 which forms the armature shaft of a motor 55 secured by bolts 56 to the bottom member 20c of frame 20 substantially centrally of said frame. Belt 52 is also engaged at the inner side of its lower run by a pulley 57 journaled on a stub shaft 58 carried in an arm 59 secured to and swinging about a pivot 60 in the side of frame 20. A tensile spring 61 is secured at one end to arm 59 and at its other end to the lower portion of frame 20, thus urging pulley 57 downwardly against belt 52. Shaft 54 also has secured thereto outward of pulley 53 a twin pulley 62 over which and in the 65 twin grooves of which runs a pair of belts 63, said belts also running over a twin pulley 64 having two grooves therein. Pulley 64 is secured to a shaft 65 journaled in bearings 66 at the top of side walls 20b, which bearings have removable caps 66a secured by the headed bolts 67. A cutter

68 of the milling cutter type is keyed to shaft 65, the same being shown as in three sections, said cutter being engaged at one end by a nut 69 threaded on shaft 65. One end of shaft 65 has a reduced threaded portion projecting outwardly of bearing 66 and a castle nut 70 is threaded thereon and engages the outer side of bearing 66. A collar 71 is pinned to the other end of shaft 65 and engages the outer side of the other bearing 66 inward of pulleys 64 so that shaft 65 is held 10 from endwise movement.

A pair of blocks 72 are secured respectively to the inner sides of bearings 66 by bolts 73. Said blocks are rectangular in vertical and horizontal cross section and have semicylindrical recesses 15 in their central portions concentric with shaft 65. Oppositely disposed bell crank levers 74 have upwardly projecting arms disposed at opposite sides of shaft 65 and are connected at their upper ends by a tensile coiled spring 75. Levers 74 have pivot 20 studs 74a journaled in bores in the blocks 72. The lower arms 74b of levers 74 extend inwardly and have lower surfaces with rounded inner ends adapted to be engaged by the top of the plate being worked upon and which is carried by the 25 slide 42. Lugs 76 are secured in blocks 72 beneath portions 74b and each has a screw 77 threaded therethrough, the inner end of which engages the bottom surface of a portion 74b adjacent block 72. It will be understood that there 30 is a pair of the levers 74 adjacent each end of cutter 68. Another lever 78 is disposed at one side of one of the levers 74, namely at the rear side thereof and has a stud 78a journaled in a bore in block 51. A tensile spring 79 is secured to 35 the upper end of lever 78 and to one side of one of the caps 66a so as to exert tension on lever 78. Lever 78 has a lower portion 78b having an undersurface with a rounded end, said portion being directed away from cutter 68. Another lug 80 40 is secured in block 72 and has a screw 81 threaded therethrough, the end of which engages the undersurface of portion 78b adjacent block 72. Screws 77 and 81 have slotted heads. It will be understood that there is one of the levers 78 adjacent and outwardly of each pair of levers 74.

Motor 55 is of the reversible type and the circuit thereof is controlled by a switch 82 having a movable contact carrying a handle 83. Switch 82 has forward and reverse contacts 82a and handle 83 50 is shown in the stop or neutral position.

Frame 29 as previously described is adapted to be raised and lowered by manipulating hand wheel 32. A plate 84 is disposed within one of the side walls 20b adjacent one side of frame 29 and 55 is held in light engagement therewith by headed screws 85 extending through side wall 20b and into plate 84. Frame 29 is thus kept from any lateral movement.

A rod 86 extends across the top of the frame 60 and is carried at its ends in arms 87 carried on pivots 88 journaled in the bearings 66 at the inner sides thereof. One of said pivots 88 extends to the outer side of its bearing 66 and has secured thereto a crank 89 having a projecting 65 handle 89a intermediate the ends thereof. Crank 89 extends downwardly through a slot in the top of a switch box 90 secured to one of the side walls 20b and has secured to its lower end a roller 91. Roller 91 engages one side of a bell crank lever 92, which side has end faces at an angle to each other adapted to be engaged by the sides of a spring pawl 93 secured at one end of the switch box 90. Pawl 93 has faces adjacent its end at an angle to each other which 75

are as stated adapted to engage the faces at the end of one arm of lever 92 respectively. Lever 92 is mounted on a pivot 94 and its other arm 92a carries a contact plate 95 connected to a binding 5 post 96 on the upper side of arm 92a, to which binding post is connected one of the conductors 97 of the motor circuit. A block 98 of insulating material is secured to one side of switch box 90 and has a contact member 99 projecting upwardly 10 therethrough and normally in engagement with contact plate 95. Contact 99 is connected to a binding post 100 at the lower side of member 98, to which post is connected the other conductor 101 of the motor circuit. Switch box 90 has a 15 step portion 90a at its top with a projecting apertured lug through which extends a plunger rod 102 equipped at its upper end with a knob 103. A coiled compression spring 104 surrounds plunger 102 bearing at its upper end against knob 103 20 and at its lower end against the top of switch box portion 90a. Plunger 102 has a collar 105 secured to its lower end within the switch box 90 and which is disposed above the outer end of lever arm 92a.

25 A casing 110 is provided disposed at one side of cutter 68, the same having horizontal top and bottom portions connected by an end wall 110a at the end remote from cutter 68. Casing 110 is mounted at one side on hinges 111 secured at 30 the top and side of frame 20 and said casing has feet 112 adjacent its other side which normally rest on one of the side portions of frame 29. Casing 110 is open at its end adjacent cutter 68 and at its side adjacent hinges 111. A shield 113 extends over the top of cutter 68, being held beneath the heads of one pair of bolts 67, said shield extending in close proximity to the end of casing 110 and in substantial alignment with the top side thereof. A chute 114 is secured to one 35 side of frame 20 and is of slightly greater longitudinal extent than casing 110. Chute 114 has an open upper end disposed substantially at the bottom of casing 110 and said chute has an inwardly extending portion 114a extending through an opening in one of the doors 21. Portion 114a 40 has a plate 114b forming a part thereof engaging the outer side of door 21 and secured thereto by screws 116. Portion 114a therefore is disposed within the frame 20 and has its open lower end disposed over a box-like receptacle 117 disposed 45 within the frame and resting on bottom portion 20c. Receptacle 117 is shown as having one or more handles 118 by means of which it may be lifted and said receptacle is removable through 50 one of the openings 20d.

55 In operation, when a plate shown as 120 in Fig. 4 is to be finished, the same is placed face downward on member 42. The plate will then be brought to the desired vertical position relative to cutter 68 and this is done by turning hand wheel 32. This turns gear 30 and swings segment 27a so that all of the links 27 are swung about their pivots 26. Member 29 and member 42 carried thereby are thus raised and are always 60 in a plane parallel to the top of member 42. When member 42 and plate 120 are thus brought to the desired position frame 29 is locked by bringing the end of screw 33 against plate 37. Frame 29 is thus held firmly in position. Screw 65 33 can be locked by moving nut 35 against the end 20a of the frame and if desired by moving nut 36 against the inner side of the frame. The switch lever 83 will now be moved to bring its contact into engagement with one of the contacts 70 82a and motor 55 will be driven. Motor 55 will

drive pulley 53 which through belt 52 will turn pulley 51 and shaft 50. Beveled gears 49 and 48 will be driven thus turning screw 47. Screw 47 will be turned in the direction to move nut 46 to the right as seen in Figs. 2 and 4. Shaft 54 5 will also drive pulley 62 and through the belt 63 the pulley 64. Pulley 64 drives shaft 65 and thus the cutter 68. Plate 120 is positioned with one end against member 46 and is held firmly 10 against this member due to the serrated edge thereof. Member 42 and plate 120 are now moved toward the cutter and as the plate approaches the cutter it engages the undersurface of the first portion 74b which as shown in Fig. 2 extends entirely across member 42. The portion 15 74b can be adjusted by adjusting the screws 71 so as to get the desired contact with plate 120. The plate is thus held down by portion 74b and slides under said portion into engagement with cutter 68 which finishes the top surface 20 of the plate 120 to a very smooth surface disposed in one plane. As the plate passes the cutter it engages the other portion 74b and is held down thereby. When it progresses a short distance farther it engages the portion 78b and 25 is held down by this portion. Said portion, of course, can be adjusted to the desired position by screws 71 and 81. The plate thus moves past cutter 68 and is finished. It will be understood that the plates vary considerably in length and 30 breadth as well as in thickness. When the plate has passed the cutter the switch lever 83 will again be moved to bring its contact into engagement with the other contact 82a and motor 55 will be reversed. Screw 47 will then move nut 35 35 40 to the left as shown in Figs. 2 and 4 and member 42 will be moved to the left with plate 120. When the plate 120 and member 42 have reached their end position switch lever 83 will be again moved to neutral position stopping the machine. 45 Suitable stops can be arranged to be engaged by a lug or lugs carried by member 42 to throw the switch 82 and levers and stop the motor 55 without the intervention of the operator. Should the plate 120 be positioned so that too great a 50 cut is attempted by cutter 68 the rod 86 will be elevated and arm 87 will be swung about pivot 88 in a clockwise direction as shown in Fig. 6. This will cause roller 91 to act on lever 92 and will raise contact plate 95 out of engagement with 55 contact 99. The motor circuit will thus be broken and the motor 55 and the machine will stop. The engagement of members 95 and 99 can be reestablished by pressing down on knob 103 and pushing plunger 102 downward against the tension of spring 104 so that collar 105 engages lever arm 92a and swings the same downwardly. Lever 92 will be held in the two positions respectively by engagement of its end surfaces by pawl 93. 60

When the cutter 68 is operating it removes chips or shavings from the top of plate 120 and these are thrown backwards as indicated by the arrows in Fig. 4. These shavings thus pass into casing 110. Shield 113 prevents any of the shavings from being thrown upwardly at the end of casing 110. When a quantity of shavings have accumulated in casing 110 the same can be swung upwardly as shown in dotted lines in Fig. 8 and the shavings will then pass into chute 114 and 65 be delivered therethrough into receptacle 117. Casing 110 will then be returned to its normal position with the leg members 112 resting on the side of member 29. It will be noted that when frame 29 is elevated that shaft 50 is moved 70 75

and this moves pulley 51. It is necessary therefore to have means for keeping belt 52 under proper tension and this is accomplished by pulley 57 which is urged against said belt by spring 61 5 moving arm 60.

From the above description it is seen that applicant has provided a very simple and efficient structure of stereotype plate finishing machine. The work is very quickly and accurately done 10 and the work can be done quite rapidly.

In practice frame 20 has been made of one integral casting. This makes it possible to get accurate positioning of frame 29 on its pivots and insures that the parts will not become dis- 15 arranged by any movement of parts of a divided frame. The machine has been amply demonstrated in actual practice and found to be very successful and efficient.

It will, of course, be understood that various 20 changes may be made in the form, details, arrangement and proportions of the parts, without departing from the scope of applicant's invention, which generally stated, consists in a device capable of carrying out the objects above set 25 forth in the parts and combinations of parts disclosed and defined in the appended claims.

What is claimed is:

1. A plate finishing machine having in combination, a single rotating tool, a plate-supporting member reciprocable past said tool, resiliently mounted presser members for engaging said plate at either side of said tool and a third presser member longitudinally spaced from one of said presser members at the discharge side of 35 said tool.

2. The structure set forth in claim 1, said third presser member comprising a lever with a convex surface engageable with said plate and resilient means acting on said lever to press said 40 surface against said plate.

3. A plate finishing machine having in combination, a rotating tool, a plate-supporting member reciprocable past said tool, a casing above said member at one side of said tool and extending 45 longitudinally of said plate supporting member for some distance and above the same and having an opening at one end adjacent said tool to receive shavings discharged thereby.

4. In a plate finishing machine having a cutter and a plate supporting member reciprocable past said cutter, the combination of a frame, a second member supporting said plate supporting member and having a surface disposed in a plane 50 parallel to the direction of movement of said plate and swinging means for supporting said second member for raising and lowering the same to adjust it for different cuts on said plate and maintaining said surface parallel to said plane including a plurality of links spaced longitudinally of said member, said links being of equal 55 length, pivots at one end of said links connecting

the same to said frame and pivots at the other ends of said links connecting the same to said second member, said links being arranged in parallel relation and manually operated means for swinging one of said links whereby all must 60 move in unison.

5. In a plate finishing machine of the type having a rotating cutter past which a plate is moved, the combination of a frame, a plate supporting member and means supporting said member having portions extending downwardly at each side of said frame, pivot pins secured in said portions and spaced longitudinally of said frame, members extending across said frame having link forming lugs thereon pivoted 10 at their upper ends on said pins, pivots connecting the lower ends of said lugs to said frame, said lugs extending in parallel relation and being of equal length between their pivots, one of said members having a projection and means manip- 15 ulatable by the operator engaging said projection to rotate said member about its pivot whereby all of said lugs are simultaneously moved in parallel relation and said plate supporting member is moved to properly adjust the plate for its 20 cut and its top surface maintained in a plane 25 parallel to a fixed plane.

6. In a plate finishing machine of the type having a rotating cutter past which a plate is moved, the combination of a frame, a plate- 30 supporting member and means supporting said member having portions extending downwardly at each side of said frame, pivot pins secured in said portions and spaced longitudinally of said frame, members extending across said frame hav- 35 ing link forming lugs thereon pivoted at their upper ends on said pins, pivots connecting the lower ends of said lugs to said frame and spaced similarly to said pivot pins, said lugs extending in parallel relation and being of equal length be- 40 tween their pivots, one of said members having a projection formed as a gear segment, a pinion 45 engaging said segment and means at one side of said machine for turning said gear and swinging said lug whereby all of said lugs are swung 50 in unison and said plate-supporting member is moved.

7. A plate finishing machine having in combination, a frame, a plate supporting means having a plane surface, a member supporting said 55 means, a plurality of members of equal length pivoted about fixed pivots in said frame and spaced longitudinally of said frame and pivoted to said last mentioned member about pivots spaced similarly to said pivots and means manip- 60 ulatable by the operator for oscillating all of said swinging members simultaneously to raise and lower said last mentioned member so that said surface always moves in parallel planes to adjust the plate for its cut.

LEONARD G. OLANDER.
